UNITED STATES PATENT OFFICE.

WILLIAM S. THOMAS, OF LOCK HAVEN, PENNSYLVANIA.

SPARK-PLUG

1,254,449.

Specification of Letters Patent. Patented Jan. 22, 1913.

Application filed June 13, 1916. Serial No. 103,384.

To all whom it may concern:

Be it known that I, WILLIAM S. THOMAS, a citizen of the United States, residing at Lock Haven, in the county of Clinton and State of Pennsylvania, have invented certain new and useful Improvements in Spark-Plugs, of which the following is a specification.

My invention consists of an improved form of spark plug of the type used on internal combustion engines to produce the spark for exploding the gas within the cylinder. One object of my invention is to produce a spark plug in such manner that a single member will be operative by a continuous movement to change the relative positions of the electrodes and to lock them in their adjusted positions.

Another object is to so construct my invention that the same member which is operative to change the position of and to lock the electrodes is also operative to position the parts in order to provide an opening through which cleaning fluid may be inserted to clean the inner parts thereof.

A further object is to so construct my invention that the several parts thereof will efficiently operate for a long period of time without requiring their removal for cleaning.

A still further object of my invention is to reinforce an insulating element of my invention that the latter will not tend to corrode, fracture, or shorten the electric circuit.

A still further object is to so construct my invention that the electrodes may be adjusted into different positions to suit the requirements of the engine without removing any of the elements from the plug proper.

Another object of my invention is to provide a spark plug in which the parts may be quickly and easily assembled or removed, and which will be durable and can be manufactured at a reasonably low cost.

These objects, and other advantageous ends which will be described hereinafter, I attain in the following manner, reference being had to the accompanying drawings in which

Figure 1 is a side elevation of my invention.

Fig. 2 is a top plan view of Fig. 1.

Fig. 3 is an enlarged sectional elevation of my invention showing the parts in the operative position occupied during the normal running of the engine.

Fig. 4 is a fragmentary view of similar nature to Fig. 3 showing several of the parts moved into a position for admitting cleaning fluid.

Fig. 5 is a sectional plan view on the line *a—a* of Fig. 3 drawn on an enlarged scale, and

Fig. 6 is a longitudinal elevation of an insulating member which I employ.

Referring to the drawings, 1 represents a metallic body portion having a screw-threaded end 2 which is provided with a cavity 3 which extends from the lower end 4. This cavity 3 is reduced in diameter as shown at 5, and thereby provides an annular shoulder or ledge 6. This reduced portion 5 extends from the shoulder 6 to the outer upper surface 7 of the body portion 1.

An insulating member 8 is provided with an annular flange 9 which produces a shoulder 10 on its upper face for engagement with the lower flanged end 11 of a metallic tube or jacket 12. The body portion 13 of the insulating member 8 fits within the jacket 12, and is cemented thereto, so that while there is no lateral pressure against the body portion 13, the cement will hold the member 8 within the jacket and also act to prevent any moisture from effecting the porcelain within said jacket.

The flanged end 11 is of smaller diameter than the diameter of the cavity 3, so that a space 14 is always present, however, the upper shoulder 15 of the end 11 abuts the shoulder 6 and normally forms a seal between the cavity 3 and the reduced opening 5.

The reduced opening 5 is of larger diameter than the jacket 12, and thus provides an annular space 16 around said jacket, this space being in communication with the atmosphere. The upper end of the jacket 12 is screw-threaded at 17, and a threaded sleeve 18 is designed to be screwed upon said threaded end. This sleeve 18 is provided with a transversely extending slot 19 through which passes a tightening screw 20, the latter being provided with screw-threads and designed to fit within a tapped opening 21 in the lower portion of the sleeve 18 and freely pass through an opening 22 in the upper portion provided by said slot 19, so that an inward movement of said screw 20 will tend to move the upper portion 23 of the sleeve 18 toward the lower portion 24 of said sleeve, and thereby jam the threaded

portion of the sleeve and the threaded portion 17 of the jacket, preventing relative movement between said sleeve and the jacket.

The jacket 12 terminates at 25, preferably 5 at a slight distance above the uppermost surface of the sleeve 18, and the porcelain body 13 extends beyond the jacket as at 26 and is provided with a tubular cover of flexible rubber 27 which normally projects 10 slightly above the upper end of the body portion 13 of the porcelain member 8, and is designed to be engaged by a screw-threaded washer 28 which is adjustably mounted on a screw-threaded binding post 29, the latter being secured within a portion 26 of the porcelain member 8, so that when this threaded washer is screwed into engagement with the upper end of the tubular cover, the latter will be compressed longitudinally and 20 form a positive seal between the threaded washer 28 and the end 25 of the jacket 12, thus effectively preventing moisture or foreign material from engaging the outer surface of the porcelain which projects beyond 25 the tube 12.

A binding nut 30 is screwed on the uppermost portion of the binding post 29, and between this nut and the washer may be secured the one end of the electric conduit or 30 wire.

A wire 31 is embedded within the central portion of the porcelain 8, and at its upper end engages the binding post 29 to form an electric contact therewith. The lower end 35 of the wire 31 is bent at an angle as at 32. This bent end 32 is screw-threaded at 33, and on the screw-threaded end is provided a metallic cap 34 which has internal screw-threads engaging the threaded end 33, thus 40 the cap 34 provides an electrode which is detachable and may be removed if desired and readily replaced.

The second electrode 35 is screwed within a tapped opening 36 in the lower end of the 45 body portion, and the spark travels between the electrode 34 and the electrode 35. The electrode 35 is provided with a slot 37 into which a screw-driver may be inserted for the insertion or removal of this electrode. The lower end 38 of the porcelain 8 is provided with a series of peripheral grooves 39 which, as shown in the drawings, are 50 annularly arranged and provide annularly projecting edges 40. The annular projections 55 thus formed by the peripheral grooves are for the purpose of increasing the electrical resistance when the porcelain becomes coated with particles of carbon, oil, or other foreign material which is produced by the 60 combustion within the engine cylinders, and this construction is such as to reduce the area over which the current has to traverse, thereby increasing the resistance and requiring very high voltage before current can 65 ground before jumping the spark gap.

A collar 41 is secured by means of a set screw 42 to the jacket 12 at a point above the uppermost surface of the sleeve 18, and this collar is provided with an indicating finger 43 which depends from the collar and 70 is movable adjacent the outer edge 44 of the body portion 1. This edge 44 is provided with a series of indicating grooves 45, and the spaces between these lines represent distances existing between the electrodes 34 and 75 35, so that by watching the indicating finger 43, the operator can tell how close the electrodes 34 and 35 are to each other.

A hand lever 46 has a yoked or bifurcated end 47 terminating in arms 48 which are 80 sufficiently far apart to span the outer diameter of the sleeve 18. Each of these arms 48 is pivoted as at 49 to the sleeve 18, each arm 48 having an edge portion 50 designed to engage the surface 7 of the body portion 85 1 when the handle is moved into the position shown in Figs. 1 and 3 to move the porcelain 8 and jacket 12 longitudinally and to clamp the shoulder 15 of the jacket 12 tightly against the shoulder 6 of the body portion 1. 90 In other words, the edges 50 act as cams to raise the jacket, with the porcelain therein, into such position as to effectively cut off the annular passage 16 from the cavity 3.

The porcelain 8 has a longitudinally extending passage 51, through which the wire 31 extends, and this passage is increased in diameter as at 52 to provide room for the binding post 29.

The wire 31 at its upper end may be attached to the binding post in any suitable manner such as by brazing or soldering, however, I preferably make the passage 52 of larger diameter than the passage 51 in order to insert a sufficiently strong binding 100 post 29.

It will be noted that with a spark plug constructed in accordance with my invention, the position of the electrodes may be 105 changed to suit the load on the engine, or for any other reason, by merely raising the hand lever 46 to permit the edges 50 to be moved free of the surface 7 of the body portion 1, since when the handle is in this raised position, the entire jacket and porcelain may 110 be rotated and thus move the electrode 34 toward or from the electrode 35 to increase or decrease the gap between said electrodes. This can be done without stopping the engine or removing any of the parts of the 115 plug and may be done quickly and easily. The indicating finger shows exactly the position of the hidden electrodes, so that after 120 the latter have been properly positioned to give the desired spark, the lowering of the hand lever 46 will lock the flange 11 against the shoulder 6 and create sufficient friction to prevent vibration from the engine or other means from further changing the relative 125 position between the electrodes.

It will thus be noted that by a simple continuous movement upwardly of the handle, and then turning the latter circumferentially of the jacket and porcelain, the positions of the electrodes may be changed and after the desired position is secured, a straight downward movement of the handle locks the parts in their operative position.

It will also be understood that when the hand lever 46 is in its raised position as shown in Fig. 4, the annular passage 16 which communicates with the atmosphere is in direct communication with the cavity 3. When the elements are in this position, cleaning fluid may be inserted through the passage 16 to clean the several parts.

Another valuable feature of my present invention is that the construction is such that the electrodes, while in their operative position, are confined within the cavity 3 and are not subject to the direct carbonization which would otherwise occur if they were permitted to remain below the end of the body portion.

Furthermore, by shaping the porcelain 8 as above described, the latter will remain clean for a great length of time as will also the other elements of my invention. If it is desired to raise or lower the electrode 34 with respect to the electrode 35, it is merely necessary to loosen the screw 20, when the sleeve may be turned relative to the jacket. This action causes a relative longitudinal movement between said sleeve and jacket.

By having the jacket surrounding the body portion of the porcelain member 8, the latter is relieved of any lateral pressure, the cement acting to keep out moisture or particles of foreign material. The annular flange on the porcelain by being in engagement with the flanged lower end of the jacket, transmits any longitudinal pressure to the jacket, thereby relieving all strain from the porcelain. This is an extremely valuable feature of my invention, since it prevents the checking or cracking of the porcelain, and in addition reduces the likelihood of the latter to shorten the circuit.

It will be understood that the edge portions 50 of the yoked end of the hand lever 46 act as cams to effect the movement of the jacket 12 within the body portion 1.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

66 1. The combination in a spark plug, of a

body portion, an electrode holder therein and including a threaded jacket and an insulating member secured therein, a sleeve adjustably secured to the jacket, and a hand lever pivoted on said sleeve and having a portion for frictional engagement with said body portion, substantially as described.

2. The combination in a spark plug, of a body portion, an electrode holder therein and including a threaded jacket, a slotted sleeve having threads fitting said threaded jacket, means for moving the portions of said sleeve, formed by the slot, to bind the sleeve to the jacket, and a lever pivoted on said sleeve and having a portion for frictional engagement with said body portion, substantially as described.

3. The combination in a spark plug, of a body portion having a recess therein reduced for a portion of its length to form a shoulder, a jacket having a flanged end providing a shoulder movable into and out of engagement with said shoulder of the body portion, an electrode carried by the jacket, and a single hand lever operative to relatively move said shoulders into and out of engagement, substantially as described.

4. The combination in a spark plug, of a body portion having a recess therein reduced for a portion of its length to form a shoulder, a jacket having a flanged end providing a shoulder movable into and out of engagement with said shoulder of the body portion, an electrode carried by the jacket, a single hand lever operative to relatively move said shoulders into and out of engagement, said hand lever having a portion designed to lock said shoulders in their engaged position, substantially as described.

5. The combination in a spark plug, of a body portion having a recess reduced in diameter for a portion of its length to form a shoulder, a jacket having a body portion of smaller diameter than the reduced diameter of the cavity, a projection formed on said jacket having a diameter larger than the reduced cavity and of smaller diameter than the main cavity, a hand lever pivotally supported by the jacket and having a portion for engagement with said body portion, and an electrode supported by said jacket, said hand lever being movable on its pivot to engage the body portion and thereby force the projection on the tube into engagement with the shoulder provided by said reduced recess, substantially as described.

6. The combination in a spark plug, of a body portion having a recess reduced in diameter for a portion of its length to form a shoulder, a jacket having a body portion of smaller diameter than the reduced diameter of the cavity, a projection on said jacket having a diameter larger than the reduced cavity and of smaller diameter than the

main cavity, a member fitting within said jacket and having a portion providing a shoulder in engagement with the inner end of the jacket, an electrode carried by said member, a sleeve adjustably secured to the jacket, a lever pivoted on said sleeve and having a portion for engagement with the body portion to move the projection on said jacket into engagement with said shoulder of the body portion, substantially as described.

7. The combination in a spark plug, of a body portion having a recess reduced in diameter for a portion of its length to form a shoulder, a jacket having a body portion of smaller diameter than the reduced diameter of the cavity, a projection on said jacket having a diameter larger than the reduced cavity and of smaller diameter than the main cavity, a member fitting within said jacket and having a portion providing a shoulder in engagement with the inner end of the jacket, an electrode carried by said member, a sleeve adjustably secured to the jacket, a lever pivoted on said sleeve and having a portion for engagement with the body portion to move the projection on said jacket into engagement with said shoulder of the body portion, a second electrode projecting into said cavity, said lever being operative to turn said jacket and member to change the relative positions between the electrodes and to lock the latter in their adjusted positions, substantially as described.

8. The combination in a spark plug, of a body portion having a recess reduced in diameter for a portion of its length to form a shoulder, a jacket having a body portion of smaller diameter than the reduced diameter of the cavity, a projection on said jacket having a diameter larger than the reduced cavity and of smaller diameter than the main cavity, an insulating member extending through said jacket and secured to the inner surface thereof, said insulating member having a depending portion extending into said cavity and an electrode extending therethrough, a binding post connecting with said electrode, an insulating cover, a member adjustable on said binding post and engaging said cover to force the latter into engagement with the jacket and to provide a seal for the insulating member, said member having a flange in abutment with the projection on said jacket, a sleeve adjustably secured to the jacket, a lever pivoted on said sleeve and having a portion for engagement with the body portion to move the projection on said jacket into engagement with said shoulder of the body portion, substantially as described.

9. The combination in a spark plug, of a body portion having a recess reduced in diameter for a portion of its length to form a shoulder, a jacket having a body portion

of smaller diameter than the reduced diameter of the cavity, a projection on said jacket having a diameter larger than the reduced cavity and of smaller diameter than the main cavity, an insulating member extending through said jacket and secured to the inner surface thereof, said insulating member having a depending portion extending into said cavity and an electrode extending therethrough, a binding post connecting with said electrode, an insulating cover, a member adjustable on said binding post and engaging said cover to force the latter into engagement with the jacket and to provide a seal for the insulating member, said insulating member having a flange in abutment with the projection on said jacket, said jacket having a screw-threaded portion, a threaded sleeve fitting said screw-threaded portion and having a slot therein extending transversely to the jacket, and means for moving the portions of said sleeve, formed by said slot, toward each other to bind the sleeve to the jacket, substantially as described.

10. The combination in a spark plug, of a body portion having a recess reduced in diameter for a portion of its length to form a shoulder, a jacket having a body portion of smaller diameter than the reduced diameter 95 of the cavity, a projection on said jacket having a diameter larger than the reduced cavity and of smaller diameter than the main cavity, an insulating member extending through said jacket and secured to the inner 100 surface thereof, said insulating member having a depending portion extending into said cavity and an electrode extending therethrough, a binding post connecting with said electrode, an insulating cover, a member adjustable on said binding post and engaging said cover to force the latter into engagement with the jacket and to provide a seal for the insulating member, said insulating member having a flange in abutment with 105 the projection on said jacket, a sleeve adjustably secured to the jacket, a lever pivoted on said sleeve and having a portion for engagement with the body portion to move the projection on said jacket into engagement 110 with said shoulder of the body portion, said insulating member having a plurality of peripherally extending grooves providing anularly extending projections, substantially 115 as described. 120

11. The combination in a spark plug, of a body portion having a recess therein reduced for a portion of its length to form a shoulder, a jacket having a flanged end providing a shoulder movable into and out of engagement with said shoulder of the body portion, an electrode carried by the jacket, and means operative to relatively move said shoulders into and out of engagement, substantially as described. 125 130

12. The combination in a spark plug, of a body portion having a recess therein reduced for a portion of its length to form a shoulder, a jacket having a flanged end providing 5 a downwardly facing shoulder, an electrode carried by the jacket, and means for moving the shoulder of the jacket upwardly into and downwardly out of engagement with the shoulder of the body portion, substantially as described.
13. The combination in a spark plug, of a body portion having a recess reduced in diameter for a portion of its length to form a shoulder, a jacket having a body portion 15 rotatable within and of smaller diameter than the reduced diameter of the cavity, said jacket being provided with a projection having a diameter larger than the reduced cavity and of smaller diameter than the main 20 cavity, a hand lever movably supported by the jacket and having a portion for engagement with said body portion, and an electrode supported by said jacket, said hand lever being movable on its support to engage 25 the body portion and thereby force the projection on the jacket into engagement with the shoulder provided by said reduced recess, substantially as described.
14. The combination in a spark plug, of a body portion having a recess reduced in diameter for a portion of its length to form a shoulder, a jacket having a body portion 30 of smaller diameter than the reduced diameter of the cavity, a projection on said jacket having a diameter larger than the reduced cavity and of smaller diameter than the main cavity, a member fitting within said jacket and having a portion providing a shoulder in engagement with the inner end of the 35 jacket, an electrode carried by said member, a sleeve adjustably secured to the jacket, a
- lever movably mounted on said sleeve and having a portion for engagement with the body portion to move the projection on said jacket into engagement with said shoulder of 45 the body portion, substantially as described.
15. The combination in a spark plug, of a body portion having a cavity reduced in diameter for a portion of its length producing a shoulder, a jacket of smaller diameter than 50 the reduced portion of the cavity and having an annular flange designed to engage said shoulder, an electrode carried by said jacket, and means including a cam for actuating said jacket to move its flange into and out of contact with said shoulder, substantially as 55 described.
16. The combination in a spark plug, of a body portion, an electrode holder therein including a jacket and an insulating member 60 therein, means on said jacket forming a support, and a hand lever movably mounted on said support and having a portion for engagement with said body portion, substantially 65 as described.
17. An electrode holder for spark plugs including a body portion for insulating material having an annularly projecting flange and a portion depending from said flange, said depending portion having a plurality 70 of peripherally extending grooves providing annularly projecting edges, said grooves being curved in cross section, substantially as described.

In testimony whereof I have signed my 75 name to this specification in the presence of two subscribing witnesses.

WILLIAM S. THOMAS.
